DEVICE FOR CLEANING AND MASSAGING
THE SCALP

Anthony F. Feix, Brooklyn, N. Y.

Application July 3, 1937, Serial No. 151,800
Renewed May 3, 1940

1 Claim. (Cl. 15—157)

The invention relates to scalp cleaning and massaging devices of the type in which the hair and scalp is agitated by a number of fingers or protrusions, and this invention has for its main object to provide a device of this kind which, while massaging the scalp, will also remove all dust, dandruff and loose hair, after a person has had his hair cut.

Another object is to provide a device which is sanitary, which is easy to operate, which has no parts easily broken or apt to get out of order, and on which appliances of different kinds may be used. A still further object is to provide a device of simple construction, which can be manufactured, sold and operated at a relatively low cost.

These and various other objects and advantages will be readily understood from the following description and from the accompanying drawing of preferred embodiments of the invention, in which, however, modifications may be made without departing from the scope of the appended claim. In the drawing:

Fig. 1 is a side view showing the device together with an electrically-driven suction device by means of which the device may be operated;

Fig. 2 is a bottom view of the device itself;

Fig. 3 is a vertical sectional view of Fig. 2, taken on the line 3—3;

Fig. 4 is a bottom view of the device shown with a different applicator; and

Fig. 5 is a vertical sectional view of Fig. 4, taken approximately on the line 5—5.

Referring now to Figs. 1, 2 and 3, the device consists of a cup-shaped handle member 10 which is provided with an air outlet 11 at its upper end and threaded at its lower end 12. An applicator 13 is threaded on the lower end of the handle member and this applicator is provided with a plane end wall having a plurality of rows of teeth 14. Between these rows of teeth elongated slots 15 are formed which obviously are large enough for hair or dandruff to pass through. An inverted, cone-shaped air duct 16 is inserted in the handle member. The device may be attached, by means of a flexible tube 17, to any suitable suction device, as for example the suction device 18 shown directly connected to the motor 19 in Fig. 1.

The device just described, and in which the teeth are rigid, is particularly well adapted for the use on persons with short hair, particularly after the hair has been cut. It is used in the

manner of a comb by passing it through the hair and the suction created will draw dust, dandruff and short, loose hair through the air duct 16, flexible tube 17 and through the suction device, from which it will be deposited in the removable bag 28 secured to the suction device.

In Figs. 4 and 5, a slightly modified applicator has been shown attached to the handle member. This applicator is preferably made of relatively soft rubber and the end wall is provided with a plurality of circumferentially arranged solid protrusions 21 having their ends convexly curved between which a plurality of orifices 22 which are obviously large enough to pass hair or dandruff are formed. As is clear from the showing in the drawing, the apertures or orifices 22 have a total area at least equal to the area of said outlet. The soft rubber from which the end wall is formed permits the end wall to concave inwardly when pressed on the scalp and therefore to conform with the contour of the head. With this applicator not only may the scalp be cleaned, but a massage action is produced. This last-mentioned applicator may either be attached to the handle member by means of a coarse thread, or may just be held thereon by friction.

There is a substantially uniform distribution of the holes and of the protrusions over the outside of the entire applicator which gives a uniform effect in loosening and removing dandruff.

Having described the invention and its objects, what I claim as new and wish to protect by Letters Patent is:

A device of the class described comprising a hollow handle member, an applicator having means for attaching it to the end of said handle, said applicator having a flat end wall of elastic material so that the wall yields inwardly to conform with the scalp when applied, a plurality of external rubber protrusions on said end wall, having solid convexly curved contact ends so that they are effective to loosen dandruff, said protrusions being distributed over substantially the entire face of said end wall, a chamber in said handle member, an outlet in said handle connecting with said chamber, and a plurality of air-suction apertures disposed in said wall adjacent the bases of said protrusions, said apertures having a total area at least equal to the area of said outlet and each aperture being sufficiently large to pass hair and dandruff.

ANTHONY F. FEIX.
